(57) **CLAIM**

The ornamental design for a shoe with a transparent pouch, as shown and described.

DESCRIPTION

FIG. 1 is a left side view of a shoe with transparent pouch, showing my new design;

FIG. 2 is a right side thereof;

FIG. 3 is a top view thereof;

FIG. 4 is a front view thereof; and,

FIG. 5 is a rear view thereof.

The broken lines in the figures are for environmental purpose only and form no part of the claimed design. Viewpoints not illustrated present no additional ornamental features over those illustrated in the present set of drawings. The bottom view of the shoe is flat and devoid of surface ornamentation.
